(57) CLAIM

The ornamental design for a day bed, as shown and described.

DESCRIPTION

FIG. 1 is a top, left, front perspective view of a day bed showing our new, original and ornamental design.

FIG. 2 is a front view of the bed shown in FIG. 1.

FIG. 3 is a left side view of the bed shown in FIG. 1.

FIG. 4 is a right side view of the bed shown in FIG. 1; and, FIG. 5 is a top plan view of the bed shown in FIG. 1 from the foot board to the head board.

The broken lines shown in the drawings are for illustrative purposes only and form no part of the claimed design.
